UNITED STATES PATENT OFFICE

172,751

BROOCH OR THE LIKE

Max B. Katz, University Heights, Ohio

Application April 30, 1954, Serial No. 30,264

Term of patent 7 years

(Cl. D45—19)

To all whom it may concern:

Be it known that I, Max B. Katz, a citizen of the United States and a resident of the city of University Heights, county of Cuyahoga, and State of Ohio, have invented a new, original, and ornamental Design for a Brooch or the like, of which the following is a specification, reference being had to the accompanying drawing, forming a part hereof.

Figure 1 is a front elevation of a brooch or the like, embodying my new design, and

I claim:

The ornamental design for a brooch or the like, substantially as shown.
